UNITED STATES PATENT OFFICE.

GERTRUDE M. GRANT, OF CHICAGO, ILLINOIS.

DRESS-SHIELD.

SPECIFICATION forming part of Letters Patent No. 712,188, dated October 28, 1902.

Application filed May 5, 1902. Serial No. 105,990. (No model.)

To all whom it may concern:

Be it known that I, GERTRUDE M. GRANT, a citizen of the United States, residing at Chicago, in the county of Cook and State of Illinois, have invented a certain new and useful Improvement in Dress-Shields, of which the following is a specification.

My invention relates to dress-shields having arm and body flaps and provided with attaching-pins.

The objects of my invention are to permit the attaching-pins to be concealed and confined between the flaps and in alternation therewith, if so desired, to be all or in part brought outside the shield in accordance with requirements or desire; to provide flexible connections between the pins and shield and to adapt such connections to form hinge-straps practically capable of universal swing or movement, whereby such hinge-straps can be brought into any desired angles with reference to convenience and conditions; to permit the convenient employment of safety-pins and to permit such pins to be easily manipulated for the purpose for which they are intended; to adapt the hinge-straps to conform to the situation; to permit the pins to swing independently of the dress-shield, as by universal joints, and at the same time attach them to the shield by flexible swinging connections adapted to yield in all directions, and to provide a simple and efficient construction forming as a whole an improved article of manufacture.

In the accompanying drawings, Figure 1 is a side view of the dress-shield with the pins and flexible hinge-straps shown in dotted lines. Fig. 2 is a perspective view of the shield with one of the flaps partially turned back. Fig. 3 is a detail, being an enlarged section on line 3 3 in Fig. 1. Fig. 4 is a detail, being an enlarged section on line 4 4 in Fig. 1.

The dress-shield comprises a pair of flaps A and B, of flexible material, united along the curved fold-line C in any known or suitable way. The flaps are termed "body" and "arm" flaps, respectively. The dress-shield thus constructed is provided with a plurality of pins D, constructed after the manner of ordinary safety-pins and attached to the dress-shield by short flexible hinge-straps E, adapt-

ed to be bent in any desired direction and so connected with the safety-pins that the latter can be swung and deflected independently of the strap-hinges. The strap-hinges are also adapted to have sufficient torsional yield to permit the pins to be turned about axes coincident with their length, and by reason of these flexible connections between the shield and safety-pins the latter are practically capable of universal movement independent of the shield. These flexible strap-hinges are attached to the margin of the dress-shield and are of a length to permit them to lie or fold in between the two flaps A and B, as in dotted lines, Fig. 1, and in full and dotted lines, Fig. 2. By this arrangement the pins can be readily attached to the garment or article of wear at points which will properly anchor the dress-shield and at the same time maintain the pins between the flaps, so as to protect them from moisture and rust. If desired, however, one or more of these flexible hinge-straps can be unfolded or swung so as to project out from the dress-shield. Two of these flexible hinge-straps are attached to the dress-shield respectively at opposite ends of the curved fold-line, and to the middle portion of the free edge of one or both flaps like flexible hinge-straps can be secured.

As a simple, economical, and preferred construction each flexible hinge-strap of desired width or diameter is bent to form a loop, which passes through an eye d at one end of one of the pins D, the terminal portions of the strap thus forming a flexible loop being secured to the dress-shield by a staple F. With such arrangement the pins can be swung in any desired direction independent of the flexible loops, and the loops may be twisted and also swung in different directions. By thus connecting the pins with the shield by joints and swinging connections the user can readily and without annoyance attach the pins to the garment or article of wear at any proper and desired points for suitably anchoring the shield, and when thus attached the flexible hinge-straps or loops and the pins on the free ends thereof will conform to the situation without discomfort to the wearer.

What I claim as my invention is—

1. As an article of manufacture, a dress-shield comprising the body and arm flaps

united along the curved fold-line, and short, flexible hinge-straps having free outer ends provided with safety-pins D, and having their inner ends secured to the shield adjacent to 5 the ends of the fold-line, and to the middle portion of the free edge of one or both flaps, the flexible hinge-straps being arranged to fold in between the flaps so as to permit the pins when attached to the garment to lie within 10 the shield, and in alternation therewith to unfold or swing outwardly so as to project out from the shield, and the pins being connected with the flexible hinge-straps to swing independently thereof as by universal joints.

15 2. As an article of manufacture, a dress-shield comprising the body and arm flaps united along the curved fold-line and loops of

flexible material forming short, flexible hinge-straps having free outer end portions provided with safety-pins D connected to the 20 straps by universal joints, and having their inner end portions secured to the shield adjacent to the ends of the fold-line, and to the middle portion of the free edge of one or both flaps, the said flexible loops being arranged to 25 fold in between the flaps so as to permit the pins when attached to the garment to lie within the shield, and in alternation therewith to unfold or swing outwardly from the shield.

GERTRUDE M. GRANT.
